INVENTOR.

Sissag K. Ouzoun-Boghossian.

UNITED STATES PATENT OFFICE.

SISSAG K. OUZOUN-BOGHOSIAN, OF HELIOPOLIS, EGYPT.

DESIGN FOR A WATCH-MOVEMENT CASE.

Application filed January 13, 1923. Serial No. 4,895. Term of patent 3½ years.

To all whom it may concern:

Be it known that I, SISSAG K. OUZOUN-BOGHOSIAN, a subject of the Sultan of Turkey (having declared my intentions of becoming a citizen of the United States of America), residing at Heliopolis, in the country of Egypt and land of Africa, have invented a new, original, and ornamental Design for Watch-Movement Cases, of which the following is a specification, refer-

ence being had to the accompanying drawing, forming a part hereof.

The figure is a perspective view of a watch-movement-case showing my new design.

I claim:

The ornamental design for a watch-movement-case, as shown.

In testimony whereof I affix my signature.

SISSAG K. OUZOUN-BOGHOSIAN.
